UNITED STATES PATENT OFFICE.

JOHN WILLIAM WALKER, OF LEEDS, ENGLAND.

HEEL FOR BOOTS AND SHOES.

No. 895,130.

Specification of Letters Patent.

Patented Aug. 4, 1908

Application filed November 19, 1907. Serial No. 402,779.

To all whom it may concern:

Be it known that I, JOHN WILLIAM WALKER, a subject of the King of Great Britain, and resident of 33 Grosvenor Place, Leeds, in the county of York, England, have invented certain new and useful Improvements Appertaining to Heels for Boots and Shoes, of which the following description, together with the accompanying sheets of drawings, 10 is a specification.

It relates to attachments for the heels of boots and shoes and especially to that class of those attachments wherein india-rubber, in conjunction with metal pieces, is employed 15 in their construction, and my said invention consists in so constructing these attachments that the metal parts as well as the india-rubber parts are made to form the wearing surfaces with the advantages of preventing 20 the user from slipping and of prolonging the wear of the parts, while said wearing parts are of such a character as to enable their ready detachment for repairs and that without the removal of any holding screws nails 25 or the like.

In the accompanying sheets of drawings:— Figure 1 is a side elevation of the heel part of a boot or shoe, illustrating the application thereto of my improved attachment. Fig. 2 30 is a view of my improved attachment as seen in the direction of arrow *a* Fig. 1. Fig. 3 is a similar view to Fig. 2 and shows the same parts as seen in the opposite direction to that indicated by said arrow *a*. Fig. 4 is a longitudinal section of a portion of the heel of a boot or shoe showing the attachment of my improved parts thereto. Fig. 5 is a view of 35 the parts shown by Figs. 1 and 4, as seen in the direction indicated by the arrow *b*. Figs. 6 and 7 are plan and sectional views of one part of my attachment shown in detail. Figs. 8 and 9 are sectional and side views of 40 certain of my attachments, and show the manner in which one part is fitted to the other. Fig. 10 is a perspective view showing 45 one of my improved parts in detail. Fig. 11 is a sectional elevation similar to Fig. 8 but shows a modification hereinafter explained.

Similar letters and figures of reference indicate similar parts throughout the several views.

In carrying my invention into effect I make use of base pieces *c* of metal which may be of cast or malleable iron or they may be 55 produced by being stamped out of sheet metal upon or over which I mount the india-

rubber parts *d* which I make to envelop same as shown by Figs. 3 and 5 so as to form a cushion between them and the heel part *f* of the boot or shoe to which they are attached 60 as hereinafter explained. The contour of the outer edge of the base piece *c* may be similar to that of the heel *f* as shown in broken lines Fig. 3 or this outline may be of the outer shape shown by Fig. 6. 65

Projecting from the base piece *c* are the prongs or studs *g* of the tapering shape shown in the several figures, their larger ends extending or being farthest from the base piece *c* to which they are secured. When 70 these base pieces *c* are of cast metal, then these projections *g* are formed integrally with them and they may be square or other shape in cross section; however when the base pieces *c* are stamped out of sheet metal 75 then the projections *g* are secured thereto as by being riveted therein, and in this case their tapering formations may be in steps or series of overhanging flanges as shown by Fig. 8. These projections *g* are formed to 80 reach through the india rubber covering *d* so that by their tapering forms they may assist in the securing of said india-rubber part *d* to the base piece *c* and so that their outer surfaces will be at all times flush therewith and 85 thus form part of the heel surface for contact with the ground over which the user is walking, in this manner fortifying or protecting the said india-rubber part *d* from excessive wear as well as forming a more 90 rigid resistance against slipping. To further secure the rubber part *d* to the base piece *c* openings *w* shown in broken lines Fig. 3, are made in said piece *c* to enable the rubber to pass through same to be joined together 95 above and below said piece *c*.

As means for attaching the base piece *c* and its covering of rubber to the heel *f* of a boot or shoe I make use of a fixing piece *h* (formed of sheet metal so that it will be 100 somewhat resilient for the purpose herein-after explained) which I secure to the heel *f* by screws or nails *k* and which has its outer edges *m* of a somewhat dovetail or extending flange shape as shown by Fig. 8, or these 105 may be of the flange shape shown by Figs. 5, 10 and 11 in order that the body part *h* may take within a correspondingly shaped groove *n* formed in the base piece *c* while the flanges *m* overhang the piece *c* at the sides adjoining 110 and at the ends of the said groove *n*.

On sliding or forcing the piece *c* into posi-

tion over the piece *h* (an opening being left between the rubber part *d* and said piece *c* for the reception of the flanges *m*) its extending ends *p* come into contact with the slightly 5 turned up edges *q* of the fixing piece *h* as the piece *c* is made to approach the inner edge *r* of the heel *f*. By the advancing movement of the piece *c* its extremities *p* pass beneath the edges *q* of the piece *h* and cause same to 10 rise until the base-piece *c* has reached sufficiently under them to be in its proper position on the heel *f*, on which the edges *q* of the piece *h* will spring back by their own resiliency for the openings *s* made through them 15 to take over projections *t* on the base-piece *c* which will thus be secured in position. To remove the attachment or base piece *c*, the insertion of an appropriately shaped instrument (such as the flattened end of a small 20 screw driver, a coin or other flattened article) between the piece *h* and the piece *c* at the parts marked *u*, *u* Fig. 5 will force the former from securing the latter and therefore its removal may be readily carried out.

25 Although I have hereinbefore described my improved parts *c* and *h* as applicable for use in conjunction with india-rubber coverings, it is obvious that by having leather pieces riveted in position on the pieces *c* 30 these may be used instead of india-rubber, since by making tapering holes in these leather pieces they will be retained by my tapering projections *g* until both are worn out, thus carrying out one of the essential 35 features of my invention without using india rubber.

Such being the nature and object of my said invention what I claim is:-

1. An attachment for heels of boots and 40 shoes consisting of a resilient plate having a fixed connection with a heel, said plate comprising a head provided with locking openings, a projecting portion carried by said head and provided with side flanges, said

head and said projecting portion being in 45 different planes to provide a shoulder at their junction, a base plate carrying locking projections and having formed therein a central groove the edges of which are adapted to be slid along the side flanges of the projecting 50 portion of the fixed plate and over the said shoulder to cause the locking projections to interlock with the locking openings in the head of the said fixed plate.

2. An attachment for the heels of boots 55 and shoes consisting of a plate having a fixed connection with the heel, said plate being of substantially T-shape, the body of which is provided with side flanges and the head with end openings, and a base plate provided 60 with a tread surface of rubber or the like and adapted to be slid over the flanges of said fixed plate and being provided with projections which interlock with the said end openings of the fixed plate to cause said plates to 65 be normally retained in a relatively fixed position.

3. An attachment for the heels of boots and shoes consisting of a resilient metal plate having a fixed connection with the heel, said 70 fixed plate being provided with depressed side flanges and end locking openings, a base plate carrying a resilient tread surface and being provided with a central groove the edges of which engage with said flanges of 75 the fixed plate when the base plate is slid thereon, and end projections carried by said base plate and adapted to interlock with the end openings in the fixed plate to normally retain said plates in a relatively fixed position.

In testimony whereof I have hereunto affixed my signature in presence of two witnesses.

JOHN WILLIAM WALKER.
